UNITED STATES PATENT OFFICE

WILLIAM J. COLLISON, OF BAKERSFIELD, CALIFORNIA

DOWN DRAFT PLUMBER'S FURNACE

Application filed April 27, 1932. Serial No. 607,844.

The invention relates to improvements in plumbers' furnaces of the type using liquid fuel and has for its principal object the improvement of such furnaces to the end that they will be more efficient in operation, operating effectively in high winds, and that will be economical in use of fuel.

A further object of the invention is the provision of an improved construction of fire pot and burner for plumbers' furnaces to the end that said parts may be used as renewal parts or replacement parts for furnaces already in use.

A further object of the invention is the provision in a plumbers' furnace of a fire pot and burner construction that is cast in one piece, the burner including a tube communicating with the lower portion of the fire pot and arcuate in shape so that its free end into which the fuel is fed opens upwardly to provide a down draft structure so that the flame most efficiently heats the tube and the heated tube in turn creates a hot flame that entirely consumes the fuel and provides a very efficient heat for the furnace.

The invention will be described in detail hereinafter and will be found illustrated in the accompanying drawings, in which

30 Figure 1 is a side view in elevation of the improved plumber's furnace,

Figure 2 is a top plan view,

Figure 3 is a sectional detail of the fire pot on a plane indicated by the line 3—3 of 35 Figure 1,

Figure 4 is a sectional detail on a plane indicated by the line 4—4 of Figure 1, and

Figure 5 is a sectional detail on a plane indicated by the line 5—5 of Figure 1, and

40 Figure 6 is a view on an enlarged scale of the plumber's furnace partly broken away and partly in section.

In the drawings similar reference characters are used to designate corresponding parts in all of the views.

The plumber's furnace is of the type utilizing gasoline or other liquid fuel, and 10 designates the storage tank for the fuel, and 11 the usual hand pump for creating air 50 pressure in the tank to force the gasoline

out of the tank through the supply tube 12, 13 designating a valve in said tube 12.

A grate 14 is spaced and supported above the tank 10 by means of legs 15 that are secured in bosses 16 on the top of the tank 10 and has a bail 17 pivotally secured thereto. 18 indicates a fire pot that is riveted or otherwise secured by means of an outstanding flange 19 to the grate 14, said fire pot 18 being bowl-shaped as shown, and 20 designates a tubular burner communicating with the fire pot 18 through the bottom 21 thereof, and bent upwardly as shown at 22 and has its free end flared outwardly as shown at 23 to add to the efficiency of the mixture of air with the gas entering the tube through a nozzle 24. The nozzle 24 is on the end of a fuel supply tube 25 that is connected to the tube 12 by means of a union 26, and leads through the fire pot 18 wherein it is coiled 65 as shown at 27, the coils being arranged slightly conical as shown in Figure 6. The needle valve 28 in the nozzle 24 controls the gas supplied to the burner and a damper plate 29 pivotally mounted as shown at 30 70 on an ear or projection 31 on the end of the burner tube 20 controls the air mixture supplied to the burner, said damper plate being provided with an arcuate slot 32 to receive the end of the nozzle 24.

33 designates a leg on the tubular burner that threadedly engages the boss 34 on a fender plate 35 that is mounted on the bosses 16 and supported by means of lugs or projections 36 thereon. The bottom 21 of the 80 fire pot 18 is provided with a plurality of openings 37 that mix air with the flame from the burner tube and furnishes an extremely hot flame in the fire pot.

Because of the arcuate shape of the burner tube 20 and its open end extending upwardly, a down draft is provided and the flame generated in the upper end of the tube by striking the curved portion 22 heats this to a high degree and thereby adds to 90 the efficiency of the burner, the down draft structure also making it possible to operate the furnace in very high winds. It will also be apparent that the provision of the down draft burner permits of using the burner it- 95 100

self as a cup for holding the liquid fuel for starting the burner, thus eliminating the necessity for a starting pan to heat the fuel supply tube to start volatilization of the gasoline or other fuel.

What is claimed is:—

In a plumber's furnace, a fuel supply tank, means to convey the fuel therefrom, a grate, legs secured to said grate and tank, 10 a fire pot secured to the grate, an arcuate tubular burner integral with the bottom of said fire pot and having its free end extend-

ing upwardly providing a down draft burner, a leg on said tubular burner, a fender plate supported above the tank and providing a heat shield therefor, the last mentioned leg secured to said plate, the means for conveying the fuel consisting of a tube traversing said fire pot and coiled therein, a valved nozzle on said tube directed into the burner, a damper plate pivotally mounted on the burner and having a slot therein to receive 75 said nozzle.
